UNITED STATES PATENT OFFICE.

HENRY J. BERY, OF DETROIT, MICHIGAN.

AIR-COMPRESSOR.

1,259,593.

Specification of Letters Patent. Patented Mar. 19, 1918.

Application filed July 31, 1916. Serial No. 112,227.

To all whom it may concern:

Be it known that I, HENRY J. BERY, a citizen of the United States, and residing at Detroit, in the county of Wayne and State 5 of Michigan, have invented a new and Improved Air-Compressor, of which the following is a specification.

This invention relates to motors and to pumps for conveying liquids and gases and 10 particularly to such pumps as are designed for compressing air and other gases, and its object is to provide a construction which will be strong and effective, which will have a minimum tendency to wear out of alignment, 15 and which will be self-lubricating.

This invention consists in two vertical aligned cylinders, the upper, a working cylinder and the lower, a guiding cylinder in which a lubricant is stored, of a pair of 20 aligned connected pistons in said cylinders, a crank shaft, intermediate the cylinders, and a connecting rod between the crank shaft and a pin carried by the piston in the guiding cylinder so that the lateral thrust of the 25 connecting rod will be received by the guiding piston which moves in a bath of oil and is therefore susceptible to very little wear.

This invention further consists in so applying the thrust of the connecting rod to 30 the aligned pistons that the side stresses on the working piston will be negligible. This invention also consists in so forming the yoke which connects the two pistons that it will intercept all particles of lubricating oil of 35 noticeable size and yet permit the passage of oily mist up to the working piston.

While this construction is particularly adapted to power driven pumps, the principle is just as applicable to motors of the 40 trunk-piston type.

In the accompanying drawing, Figure 1 is a view, partly in elevation and partly in section of this improved device. Fig. 2 is a horizontal section through the axis of the 45 crank shaft.

The particular machine shown in the drawing is an air or gas compressor consisting of a base 1 and an electric motor 2 mounted thereon, both shown conventionally. A pedestal 3 supports the shell 4 on which is formed the working cylinder. The inlet valve 6 and discharge valve 7 may be of any desired construction. A guiding cylinder 8 is connected to the pedestal 3 and is 55 intended to contain an amount of lubricating

oil, preferably enough to half fill the cylinder.

A crank shaft 10 is mounted in ball bearings 11 carried by the base 1 and the shell 4. The crank 12 has a pin 13 that extends 60 through the upper end of the connecting rod 14. The lower end of this rod extends down into the guiding piston and receives the wrist pin 15 carried by the piston 16. The working piston 17 may have rings 18 and is 65 connected to the guiding piston by means of the yoke 19. It will be noticed in Fig. 2 that there is little space between the side walls of the yoke and the sides of the shell 4, but that there is more space between the 70 yoke and the back of the shell and the cover 20.

While any desired means may connect the motor and the shaft 10, a pulley-fly-wheel 22 on the shaft 10, a pulley 23 on the motor 75 shaft, a belt 24 and a tightener 25 are preferred.

The pistons of motors and pumps usually wear egg-shaped because of the angular stresses from and to the connecting rods. 80 In the present case this is substantially prevented for the lateral thrust and pull of the connecting rod is communicated to the piston 16 which is substantially submerged in oil and thus liable to very little wear. The 85 lateral stresses on the piston 17 are so small that they need not be considered and nine months of uninterrupted operation of one of these pumps has not worn the piston 17 an appreciable amount. 90

When the piston 16 goes down into the oil in the cylinder 8, some of this oil will be splashed up and to some extent turned into a mist which will pass up between the upper end of the yoke 19 and the walls of the 95 shell 4 and settle on the piston 17, keeping it sufficiently lubricated. The splashed up particles will lubricate the crank pin 13, while the wrist pin 15 will usually be submerged at each stroke. It will be understood 100 that this invention may be applied to any type of machine having two opposed cylinders and connected pistons.

I claim:

1. The combination of two vertically opposed cylinders, the upper being a working cylinder and the lower a guiding cylinder, a pair of connected pistons working in said cylinders, a crank shaft extending intermediate said cylinders and a crank and 110

pin on said crank shaft, a wrist pin mounted in the lower or guiding piston, and a connecting rod extending between said pins and transmitting substantially all lateral 5 thrusts to the guiding cylinder.

2. The combination of vertically opposed guiding and working cylinders, the latter being above the former, the guiding cylinder being employed to hold a lubricant, a 10 working piston in the working cylinder and an open ended guiding piston in the guiding cylinder, a yoke connecting said pistons, a wrist-pin in the lower piston, a shaft extending through said yoke and having a 15 crank and crank pin, a connecting rod between the crank-pin and wrist-pin, and a shell inclosing the yoke, and so proportioned as to prevent particles of lubricant from being splashed up onto the working cylinder 20 while permitting a mist of lubricant to pass upward thereto.

3. The combination of vertically opposed guiding and working cylinders, the latter being above the former, the guiding cylinder being employed to hold lubricant, a 25 working piston in the working cylinder and a tubular guiding piston in the guiding cylinder and connected to the working cylinder, a crank shaft having a crank pin, a wrist

pin in the guiding piston, and a connecting 30 rod extending from the crank pin to the wrist pin, all lateral stresses from the connecting rod being transmitted to the guiding cylinder, the action of the guiding piston being to cause a mist of lubricant to pass 35 up into the working cylinder.

4. The combination of two vertically opposed cylinders, the upper being a working 40 cylinder and the lower a guiding cylinder, hollow pistons in said cylinders, a yoke connecting the pistons, a crank shaft extending into said yoke, a wrist pin mounted in the lower end of the lower piston, a connecting rod extending from the crank shaft into the lower piston to the wrist pin, all lateral 45 thrusts of the connecting rod being thus conveyed to the guiding cylinder, and means to revolve the crank shaft.

5. The combination of two vertically opposed cylinders, the upper being a working 50 cylinder and the other a guiding cylinder, connected pistons in said cylinders, a crank shaft, a wrist pin carried by the guiding piston, and a connecting rod between the wrist pin and crank shaft, all lateral stresses of 55 the connecting rod being thus conveyed to the guiding cylinder.

HENRY J. BERY.
